(57) **CLAIM**

The ornamental design for a stair assistance device, as shown and described.

DESCRIPTION

FIG. 1 is a top perspective view of a stair assistance device showing our new and original design;

FIG. 2 is a front view thereof;

FIG. 3 is a rear view thereof;

FIG. 4 is a top view thereof;

FIG. 5 is a bottom view thereof;

FIG. 6 is a bottom perspective view thereof.

The broken line portion of the figure drawings is included to show portions of the article that form no part of the claimed design.

1 Claim, 6 Drawing Sheets
